FLOATING FRAME FOR REDUCTION OF ROAD VIBRATION

Filed May 9, 1929

Inventor:
A. Schneider
by Gustav Wenzel

UNITED STATES PATENT OFFICE

ANTON SCHNEIDER, OF ESCHELBACH, BADEN, GERMANY

FLOATING FRAME FOR REDUCTION OF ROAD VIBRATION

Application filed May 9, 1929, Serial No. 361,766, and in Germany May 18, 1928.

Present methods of road construction, whose substructure consists of layers of road metal, concrete, stones and similar material, have the disadvantage, that the vibration 5 cause on the surface of the road by heavy passing vehicles, coupled with the recurring seasonal swelling and sinking of the earth masses, create fissures or cracks. It is further disadvantageous, that the vibrations 10 caused by motortrucks and similar heavy vehicles can spread in all directions causing vibration of buildings, which might lead to the formation of cracks. These disagreeable effects are a source of annoyance and discomfort to the occupiers of the dwellings thus shaken and cracked.

By this invention such defects are greatly reduced or entirely eliminated. Wedge-shaped rib supports movably connected with each other are arranged in the longitudinal direction of the road below the cover of the road. These supports are like rails arranged at equal distances apart parallel to each other, and connected with the road surface. By this arrangement, which is like a floating street frame the shearing forces of rolling loads are absorbed and the vibrations are thus reduced or done away with, the vibration 30 waves being distributed over a great street length where the last outrunners of the shearing forces terminate in the points of the wedge-shaped rib supports.

Presumably no vibration coming from the road will shake the buildings on either side of it, because the shearing forces in the road bed are carried along the longitudinal direction and are thus prevented from exerting any lateral effect.

The supports are ribs joined one to the other as high webs, the lower parts of said webs being waved, serrated, straight or of other shape, and automatically dig themselves into the ground like long roots.

Thus earth channels are formed within the solid rib frames within which the expanding and contracting earth masses can spend their effects without influencing the road surface.

An embodiment of the invention is illus-

trated by way of example in the accompanying drawings in which:

Fig. 1 shows a side view of the rib-like support.

Fig. 2 is a cross section through the highest rib-point of each rod. 55

Fig. 3 shows in top plan view the support as it lies in the ground.

Fig. 4 shows a means of connecting two supports. 60

Fig. 5 shows in top plan view a complete support element without enlarged head joint as may be used for fixed in roads.

Fig. 6 is a cross-section of a road showing the embedded supports. 65

The faces a' , a^2 and a^3 of the end a serve as a connection piece and b the surfaces b' , b^2 , b^3 and b^4 on the end b of the support serve as beds and abutments for two adjoining supports which mutually take up the shearing 70 forces which converge from the road surface.

The head end b of one support is inserted in the recesses f and f' in the head of the preceding support and secured in position by means of a tie rod c and bolts d . The end b 75 of the adjoining support rests securely between the arms f^2 , f^3 , f^4 , f^5 , which also positively prevent any shifting in lateral direction.

The support ribs g penetrating into the 80 ground as shown in Figs. 2 and 6, may be wave-shaped as shown by the curve g' , serrated or of other suitable shape according to the nature of the ground. They are firmly connected to the road covering g^2 as shown in 85 Fig. 6. The road surface covering may be made in one piece, or composed of several sections.

I claim:

1. A vehicle road construction comprising 90 a concrete road bed, a plurality of ribs integral with said road bed, embedded in the substructure, extending lengthwise of the road, and spaced apart transversely of the road intermediate of the side edges of the 95 latter, each of said ribs being formed of concrete sections wedge-shaped in vertical transverse section whereby they may dig themselves into the substructure when subjected to vehicle shocks, the end of each section over- 100

lapping the adjacent end of the next section, and the depth of each rib being greater at its end than at an intermediate point, and of greater depth than the spacing between adjacent ribs, and a tie rod extending lengthwise of each section, said tie rods being secured together at said overlapping ends.

2. A vehicle road construction comprising a concrete road bed, a plurality of comparatively deep concrete ribs integral with said road bed and embedded in the substructure, said ribs extending lengthwise of the road and spaced apart transversely of the road intermediate of the side edges of the latter, each of said ribs being wedge-shaped in vertical transverse section whereby they may dig themselves into the substructure when subjected to vehicle shocks, and being formed of concrete sections interlinked at their ends, and rods extending between the jointure of the interlinked sections to effect a vertically flexible joint between adjoining rib sections.

3. A vehicle road construction comprising a concrete road bed, and a plurality of ribs integral with said road bed and embedded in the substructure, said ribs being wedge-shaped in vertical transverse section in such a way as to permit them to dig themselves into the substructure when subjected to vehicle shocks, and extending lengthwise of the road and spaced apart transversely of the road intermediate of the side edges of the latter, each of said ribs being formed of concrete sections interlinked at their ends.

25 In testimony whereof I affix my signature.
ANTON SCHNEIDER.
